(57) CLAIM

The ornamental design for a part of a hair comb, as shown and described.

DESCRIPTION

FIG. 1 is a front-lower perspective view of a part of a hair comb illustrating our ornamental design;

FIG. 2 is a front-upper perspective view thereof;

FIG. 3 is a second front-upper perspective view thereof;

FIG. 4 is a rear-upper perspective view thereof;

FIG. 5 is a front elevation view thereof the rear being a mirror image;

FIG. 6 is a right-side elevation view thereof;

FIG. 7 is a left-side elevation view thereof;

FIG. 8 is a top plan view thereof; and,

FIG. 9 is a bottom plan view thereof.

Those portions shown with dashed lines are for illustration purposes only, forming no part of the claimed design.
